UNITED STATES PATENT OFFICE

2,074,840

BOBBIN TESTER

Charles D. Greentree, Schenectady, N. Y., assignor
to General Electric Company, a corporation of
New York

Application June 29, 1935, Serial No. 29,177

4 Claims. (Cl. 73—51)

My invention relates to balance-testing devices and concerns particularly apparatus for testing the balance of bobbins used in textile mills.

Most textile mills utilize many thousands of high-speed spindles. Wooden bobbins on which the thread is to be wound are slipped over these spindles and then rotate with the spindles at speeds of approximately ten thousand revolutions per minute, thus winding the thread on to the bobbins. If these wooden bobbins are out of balance, considerable vibration will be caused. This vibration, in turn, will cause the spindles to throw oil on the thread to be wound on to the bobbin and will sometimes cause breaking of the thread due to the jerky motion of the bobbin-winding action. Furthermore, an unbalanced bobbin will cause the spindle to wear out very quickly.

It is an object of my invention to obviate these difficulties by providing a simple and easily operated device for quickly testing the balance of the bobbins before they are admitted to the mill floor to be used on the spindles.

Other and further objects and advantages will become apparent as the description proceeds.

In carrying out my invention in its preferred form, a spindle and base are set up in a semiflexible type of mounting with a vibration-detecting device, such as a phonograph pick-up, attached to the lower part of the base. An indicating lamp and a suitable amplifier connected between the vibration detector and the lamp circuit are provided to produce indications whenever a bobbin being tested exhibits excessive unbalance.

The features of my invention which are believed to be novel and patentable will be pointed out in the claims appended hereto. A better understanding of my invention may be obtained from the following description taken in connection with the accompanying drawing in which Fig. 1 is a view in perspective of apparatus constructed in accordance with my invention; Fig. 2 is an elevation of the apparatus of Fig. 1 showing the enclosing case in cross section; Fig. 3 is a diagram of the electrical circuits of the apparatus; Fig. 4 is a view partially in section showing more in detail the arrangement of the spindle and base of Figs. 1 and 2, and Fig. 5 is an exploded detailed view of a portion of the vibration detector.

Referring now more in detail to the drawing in which like reference characters are used to designate like parts throughout, I have shown a standard textile mill bobbin 11 mounted upon a textile mill spindle 12 of standard manufacture. Such spindles are customarily of the self-centering

type mounted in a bearing housing or base 13. The spindle carries a pulley 14 to permit rotation of the spindle by a belt 15 driven by a motor 15' and is arranged to have the bobbin 11 mounted on the upper end of the spindle. The lower portion of the spindle 12 is rotatably supported in the base 13. The spindle 12 and the base 13 with all the details thereof are of the standard construction used in large numbers in textile mills and need, therefore, not be further described.

In my apparatus, however, a special mounting is provided for the spindle and base. The arrangement is preferably such that the spindle and base are semiflexibly mounted in that they are free to oscillate about the mounting in one plane but not in a plane perpendicular thereto. This type of mounting may be accomplished by means of a spring strip 16 having an annular portion 17 in the middle thereof or, if desired, by a pair of spring strips 16 having semicircular portions at the middle thereof adapted to surround the base 13 near the upper end thereof. It will be understood that the nut 18 and the washer 19 are tightened against the edge of the portion 17 of the spring strip 16 to insure the security of the mounting of the spindle and base. The ends of the spring strip 16 are preferably rigidly fastened in suitable slots in the frame or in the walls of an enclosing case 20.

A vibration detector of any suitable type, such as an electromagnetic phonograph pickup 21, is attached to the lower end of the base 13. Such an electromagnetic pick-up may be of the type and construction described more in detail in United States Patent No. 1,906,615 to Kendall, assigned to the same assignee as the present application. The pick-up 21 is adapted for attachment to a protruding needle and I provide a clamping arrangement 22 having a needle portion 23 adapted for attachment to the pick-up 21. The clamping arrangement 22 may consist simply of a collar 24 adapted to surround the end of the base 13 having the needle 23 attached thereto axially and having knurled headed screws 25 to permit clamping the collar 24 to the base 13.

The type of pick-up 21 shown in the drawing consists of a permanent magnet 26 with pole pieces 27 and 28. The pole pieces 27 and 28 have their polar projections divided into two parts, 29, 30 and 31, 32, respectively. An armature 33 of magnetizable material is pivotally mounted in the air gap between the pole pieces and is transverse to the direction of the lines of flux crossing from pole portion 30 to pole portion 32 and from pole portion 29 to pole portion 31.

A coil 34 is so mounted as to surround the armature 33. The coil 34 is connected to an amplifying unit 35 which, in turn, is connected to an indicating lamp 36.

5 The electrical circuit of the amplifier 35 is shown in Fig. 3. The amplifier 35 comprises a three-element electric discharge device 37 which may be of the gas or vapor filled type, for example, including an anode 38, a cathode 40, and a control electrode 41. Power is supplied by an alternating-current source 38. A transformer 42 energized by the source of current may be provided for heating the cathode 40 and a full-wave rectifier 43 of the copper oxide type, for example, 10 energized by the source 38 through a transformer 44 may be provided for supplying a unidirectional biasing voltage to the control electrode 41. Preferably, a condenser 45 is connected across the output terminals of the rectifier 43 to stabilize the control electrode circuit and the transformer 44 is connected to the source 38 through a potentiometer 46 to permit adjustment of the magnitude of the bias supplied to the control electrode 41. The coil 34 of the pick-up 21 15 is connected to the control electrode circuit of the tube 37, preferably through a transformer 47.

As the apparatus will ordinarily be used only to determine whether the bobbins tested should be rejected or accepted without any qualitative 20 determination as to the degree of unbalance, the apparatus is so adjusted before making tests on a lot of bobbins that the lamp 36 lights up whenever an undesirably unbalanced bobbin is placed upon the spindle 12 but remains dark when the 25 bobbin tested is perfectly balanced or its degree of unbalance is within permissible limits. This adjustment is most conveniently made by placing upon the spindle 12 a bobbin which has been found in actual service to be satisfactory. The 30 potentiometer 46 is then adjusted by means of the knob 48 to the point at which the lamp 36 is just caused to go out. Thereafter, when a defective bobbin is placed upon the spindle 12, the spindle 35 will be set in vibration, causing the vibration 40 detector 21 to light the lamp 36.

In response to the vibration, the armature 33 of the pick-up 21 oscillates about its pivotal axis between the pole pieces 27 and 28. It will be seen that, when the armature 33 is deflected toward 45 the pole portions 32 and 29, the minimum reluctance of the magnetic circuit will be through these pole portions and, when the armature 33 is deflected toward the pole portions 30 and 31, the minimum reluctance will be through the 50 latter pole portions. Consequently, the direction of the flux lengthwise through the armature 33 will reverse at the frequency of oscillation of the spindle 12 and the variation in reluctance will depend upon the amplitude of vibration caused 55 by unbalance of the bobbin 11. Relative motion between the armature 33 and the pole pieces 27 and 28 occurs when the base 13 vibrates because the inertia due to the mass of the pick-up 21 tends to hold it stationary in space and the flexibility 60 of the armature pivot permits such action. On the other hand, the armature 33 is rigidly attached to the base 13 and must partake of its 65 vibration.

The variations in reluctance of the magnetic circuit will cause variations in flux threading the coil 34 and, consequently, alternating voltages will be induced in the winding 34 which are amplified by the tube 37. However, when the magnitude of 5 the voltage is below a predetermined value, depending on the adjustment of the potentiometer 46, the voltage will be insufficient to overcome the bias of the electrode 41 and the tube 37 will remain unaffected. When the voltage in the coil 10 34 exceeds this predetermined value, the tube 37 will be made conducting and a current will flow through the indicating lamp 36. It is thus apparent that, by adjustment of the potentiometer 15 46, the apparatus may be adjusted to segregate bobbins having any degree of unbalance according to the desires of the mill operator or the requirements of the machinery of the mill.

In accordance with the provisions of the patent statutes, I have described the principle of operation of my invention together with the apparatus which I now consider to represent the best embodiment thereof but I desire to have it understood that the apparatus shown is only illustrative and that the invention may be carried out by other means.

What I claim as new and desire to secure by Letters Patent of the United States is:

1. A balance-testing device for rotating objects comprising in combination, a rotatable vertical spindle for carrying an object to be tested in rotation, a base carrying said spindle, flexible mounting means supporting said base near its upper end, said base being wholly supported thereby, means for rotating said spindle, an electro-magnetic pick-up mounted upon the lower end of said base, and current-responsive means electrically connected to said pick-up.

2. A balance-testing device for rotating objects comprising in combination, a rotatable spindle for carrying an object to be tested in rotation, means for flexibly supporting said spindle solely at a point intermediate its ends, means for rotating said spindle, said spindle being adapted to have the tested object mounted on the portion thereof toward one end, and a vibration-responsive device mounted at the other end of said spindle.

3. A balance-testing device for rotating objects comprising in combination, a rotatable spindle for carrying an object to be tested in rotation, a bearing housing in which one end of said spindle is supported, the other end being adapted for mounting the object to be tested, a spring strip with its ends rigidly supported and attached at the middle to said bearing housing to provide a flexible support therefor, a vibration detector mounted on said bearing housing at a point spaced from the point of attachment of said spring strip, and means for rotating said spindle.

4. A balance tester for textile mill bobbins comprising in combination, a textile mill spindle and base, means for rotating the spindle, a spring strip mounting for said base, and a vibration detector mounted upon the lower end of said base, said base being wholly supported by said mounting.

CHARLES D. GREENTREE.
